INSUFFLATOR

Lester D. Crain, Los Angeles, and Milton J. Hubbard, Inglewood, Calif.; said Hubbard as signor to said Crain

Application March 2, 1932. Serial No. 596,346

14 Claims. (Cl. 128—266)

This invention relates to and has for a purpose the provision of a simple and compact device by which fluid substances, such as a highly hygroscopic medicinal powder, can be insufflated into any orifice of the human body with the utmost ease and convenience.

It is a further purpose of the invention to provide an insufflator structurally characterized by means enabling relatively small quantities or doses from a supply of the powder stored in the device to be insufflated at the will of the operator.

A further purpose of the invention is the provision of an insufflator with which a cartridge containing the medicinal powder is adapted to be associated in a manner to practically seal the powder against exposure to moisture in the air, while enabling the powder to be discharged for insufflation under the control of the operator.

One form of the invention will be described and its novel features then pointed out in claims.

In the accompanying drawing,

Figure 1 is a view showing in plan one form of insufflator embodying this invention;

Figure 2 is a view of the insufflator in side elevation;

Figure 3 is a view similar to Figure 2, but showing a portion of the device in vertical central section;

Figure 4 is a transverse sectional view taken on the line 4—4 of Figure 3;

Figure 5 is an enlarged detail sectional view taken on the line 5—5 of Figure 3;

Figure 6 is a longitudinal central sectional view of the medicant containing cartridge which is particularly adapted for use with the insufflator.

Referring specifically to the drawing, in which similar reference characters designate similar parts in each of the several views, this invention in its present embodiment comprise a magazine 40 in the form of a cylinder one end of which is open and the other end closed and provided axially with an outlet port 10 providing communication between the interior of the magazine and the bore of an open ended tube 11 secured to the closed end of the magazine to extend diametrically thereof.

Rotatably mounted in the tube 11 is a valve V in the form of a second and smaller tube 12 which is provided with a port 13 adapted to be brought into and out of registration with the port 10 to accordingly permit or prevent the discharge of medicant from the magazine. The tube 12 is provided with a flange 14 and with an enlarged and knurled portion 15 from which latter the tube is considerably reduced in diameter and

frictionally fits into a compressible bulb B of rubber, operating when compressed manually to force a blast of air through the tube 12 and then out of the remote end of the tube 11.

The flange 14 and the knurled portion 15 are spaced apart to define an annular groove 16 into which projects a lip 17 formed on a lug 18 fixed to the tube 11, for co-action of the groove and lip in confining the tube 12 against axial displacement from the tube 11 while permitting rotation of the tube 12 to open and close the valve. The lug 18 extends across a recessed portion of the flange 14 providing stop shoulders 19 and 20, (Figure 5), one of which co-acts with the lug to limit rotation of the tube 12 in one direction to the position wherein the ports 10 and 13 register as shown in the drawing. The other stop shoulder limits the rotation of the tube in the reverse direction to a position wherein the ports are out of registration, as will be understood. The tube 11 is provided with a sight opening 21 through which suitable indicia on the tube 12 can be viewed to indicate whether the valve occupies open or closed position.

For use particularly with the insufflator, a cartridge C containing the medicinal powder to be used is preferably employed. This cartridge comprises an open ended cylinder 22 of transparent material such as celluloid, normally closed at one end by a flanged cap 23, and at its opposite end by a cupped disk 24 which frictionally fits into the cylinder and functions as a piston in the use of the cartridge with the device. The cartridge as above described is packaged for sale in a destructible wrapper 25 which hermetically seals the contents of the cartridge.

With the wrapper 25 and the cap 23 removed from the cylinder 22, the latter, which is of an external diameter to be snugly received in the magazine, is inserted open end foremost into the magazine, after which a coil spring 26 and then a closure cap 27 are applied as shown in Figures 3 and 4. A conventional bayonet slot and pin connection 28 (Figure 2) detachably secures the closure cap to the magazine with the ends of the spring 26 abutting the inner wall of the closure cap and the disk 24 so as to constantly urge the latter inwardly of the cylinder and thus operate to force powdered medicine from the cartridge into the tube 12, when its port 13 is brought into registration with the port 10.

The side wall of the magazine is provided at diametrically opposed points with longitudinal slots 29 through which the contents of the cartridge can be observed in order for the operator

to ascertain the amount of medicant in the cartridge. Axially disposed on the inner side of the disk 24 is a projection 30 which is adapted to enter the ports 10 and 13 when all of the medicant has been forced from the cylinder 22 and the disk abuts the closed end of the magazine. In this position of the disk, the projection 30 will operate to lock the valve V against rotation, as an indication to the operator that the cartridge 10 has been emptied of its contents.

10 In the operation of the insufflator, a filled cartridge C, from which the wrapper 25 and cap 23 have been removed, is inserted into the magazine, it being understood that it is desirable to have the valve V in its closed position during this operation. The spring 26 and the closure cap 27 are then applied.

Upon moving the valve tube 12 to its open position by grasping the magazine in one hand and rotating the bulb B with the other, the spring 20 26 will force a small quantity of the medicant powder from the cartridge through the registering ports 10 and 13 into the bore of the tube 12. The tube 12 is now reversely rotated to move the port 13 out of registration with the port 10. 25 The small quantity or dose of powder in the tube 12 can be now blown therefrom by compressing the bulb B. Any suitable form of applicator (not shown) can be applied to the free end of the tube 10 for insertion into the orifice 30 of the body to be treated. It will be understood that the medicant powder is of a character to render it non-packing so that each time the valve is opened, the spring 26 and the disk 24 will 35 contract to force a small quantity or dose of the powder from the cartridge into the bore of the valve tube 12 for ejection as desired.

40 The use of the cartridge and the manner in which it is associated with the device render it possible to utilize a soft and amorphous powder (non-crystalline), rather than the ordinary crystalline powder required for the present types of insufflators which have to be packed full by repeatedly pressing upon the powder in the manner 45 of filling a capsule. By the use of the soft and amorphous powder, proper insufflation is secured, with a complete diffusion of the particles on the membrane where they almost instantly dissolve and provide medication for hours, as compared 50 with minutes when the same ingredients are applied in solution.

55 What is claimed is:

1. An insufflator comprising: means for storing a supply of powder; means for urging the powder to discharge from the first means; valved means by which a dose of the powder can be separated from the supply; and means for insufflating the dose.

60 2. An insufflator comprising: a magazine in which a supply of powder is adapted to be stored, the magazine having an outlet port for the powder; means for urging the powder to discharge from the magazine through said port; a valve for controlling the discharge of powder from said 65 port and by which a dose of the powder can be separated from the supply in the magazine; and means for insufflating the dose of powder.

70 3. An insufflator comprising: a magazine in which a supply of powder is adapted to be stored, the magazine having an outlet port for the powder; means for urging the powder to discharge from the magazine through said port; a valve tube mounted for movement and having a port disposed to be registered with the first port when the tube occupies one position, for the discharge 75

of powder from the magazine into the valve tube; and means for ejecting the powder from the valve tube.

4. An insufflator comprising: a magazine in which a supply of powder is adapted to be stored, 80 the magazine having an outlet port for the powder; a spring pressed piston in the magazine for urging the powder to discharge therefrom through said port; a valve for controlling the discharge of powder from said port; and means for subjecting to a blast of air powder discharged from the magazine. 85

5. An insufflator comprising: a magazine having an outlet port; a powder containing cartridge in the magazine having an open end exposed to the port, and a piston closing its other end; means 90 co-acting with the piston to force the powder from the cartridge through said port; and means for subjecting to a blast of air, powder discharged from the cartridge. 95

6. An insufflator comprising: a magazine in which a supply of powder is adapted to be stored; the magazine having an outlet port for the powder; a spring pressed piston for forcing the powder to discharge from the magazine; a movably mounted valve tube having a port disposed to register with the first port when the tube occupies one position, for the discharge of powder from the magazine into the valve tube; means for ejecting powder from the valve tube; and 100 means on the piston adapted to enter said ports and lock the valve tube against movement when the piston is forced to one extreme position. 105

7. An insufflator comprising: a magazine in which a supply of powder is adapted to be stored; means for forcing powder from the magazine; a valve for controlling the discharge of powder from the magazine; means for subjecting powder discharged from the magazine, to a blast of air; and means for locking the valve against 110 movement when the contents of the magazine 115 has been discharged therefrom.

8. An insufflator comprising: a magazine adapted to receive a supply of powder and having an outlet port for the discharge of powder from the magazine; a tube on the magazine communicating intermediate its ends with said port; a valve tube rotatably mounted in the first tube and having a port disposed to be brought into and out of registration with the first port during rotation of the valve tube; means for forcing powder from the magazine into the valve tube when 120 said ports are in registration; and means for subjecting powder in the valve tube to a blast of air so as to eject the powder therefrom. 125

9. An insufflator comprising: a magazine adapted to receive a supply of powder and having an outlet port for the discharge of powder from the magazine; a tube on the magazine communicating intermediate its ends with said port; a valve tube rotatably mounted in the first tube and having a port disposed to be brought into and out of registration with the first port during 130 rotation of the valve tube; means for forcing powder from the magazine into the valve tube when said ports are in registration; and means for locking the valve tube against rotation when the contents of the magazine has been forced therefrom. 135

10. An insufflator comprising: a magazine 140 adapted to receive a supply of powder and having an outlet port for the discharge of powder from the magazine; a tube on the magazine communicating intermediate its ends with said port; a valve tube rotatably mounted in the first tube 145

and having a port disposed to be brought into and out of registration with the first port during rotation of the valve tube; a spring pressed piston in the magazine for forcing powder from the latter when said ports are in registration; and a compressible bulb on the valve tube for forcing air through the latter to eject powder in the valve tube therefrom.

11. An insufflator comprising: a magazine adapted to receive a supply of powder and having an outlet port for the discharge of powder from the magazine; a tube on the magazine communicating intermediate its ends with said port; a valve tube rotatably mounted in the first tube and having a port disposed to be brought into and out of registration with the first port during rotation of the valve tube; a spring pressed piston in the magazine for forcing powder from the latter when said ports are in registration; means for subjecting powder in the valve tube, to a blast of air so as to eject the powder from the tube; and a projection on the piston disposed to enter said ports when the piston has been forced to one extreme position, so as to lock the valve tube against rotation.

12. An insufflator comprising a magazine for a supply of powder; the magazine having an outlet

80
let tube and an outlet port communicating with the interior of the tube; a valve tube movably mounted in the outlet tube to control said port and enable a dose of powder to discharge from the magazine and be separated from a supply therein; and means for ejecting the dose from the outlet tube.

13. An insufflator comprising a magazine for a supply of powder; the magazine having an outlet tube and an outlet port communicating with the interior of the tube; a valve tube movably mounted in the outlet tube to control said port and enable a dose of powder to discharge from the magazine and be separated from a supply therein; and means for ejecting the dose from the outlet tube by a blast of air through the valve tube.

14. An insufflator comprising: a magazine in which a supply of powder is adapted to be stored, the magazine having an outlet port for the powder; a valve tube mounted for movement and having a port disposed to be registered with the first port when the tube occupies one position, for the discharge of powder from the magazine into the valve tube; and means for ejecting the powder from the valve tube.
